UNITED STATES PATENT OFFICE

2,090,937

BAG

Daisy H. Cohen, New York, N. Y.

Application January 23, 1936, Serial No. 60,439

10 Claims. (Cl. 150—34)

My invention relates to bags. More particularly, it relates to handbags, pocketbooks and under-the-arm bags adapted for ladies' use.

One of the objects of my invention is to provide a bag of the character described in which the opening and closing mechanism thereof is at the same time adapted to serve as a holder for ladies' gloves, handkerchiefs and the like, and in which the holding means may be effectively operated without the necessity of opening or closing the bag.

A further object of my invention is to provide a bag having a locking device of the character described, of simple construction, which will be economical to manufacture; which shall be ornamental and at the same time, operate with a high degree of efficiency for the purposes intended.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a perspective view in elevation of a lady's hand bag embodying my invention and shown in closed operative position;

Fig. 2 is a view in section taken substantially on the line 2—2 of Fig. 1;

Fig. 3 is an enlarged detail view in section taken substantially on the line 3—3 of Fig. 2;

Fig. 4 is an end view in elevation of the Fig. 1 form of device, but showing the bag in opened position;

Fig. 5 is a fragmentary view in perspective of the Fig. 1 form of device but illustrating a modified form of locking device and glove holder;

Fig. 6 is an end view in elevation similar to Fig. 4 but illustrating a different type of bag and a modified form of locking and glove holding device;

Fig. 7 is a fragmentary view in perspective of the Fig. 1 form of bag but illustrating a modified form of my invention; and

Fig. 8 is a fragmentary view in front elevation of the Fig. 1 form of bag but illustrating still another modified form of my invention.

Referring now in detail to the drawing, and particularly to Figs. 1 to 4, there is disclosed a well-known type of lady's bag 10 having the ad-

jacent bottom and side edges fastened together and the free edges at the top of the bag provided with a separable frame comprising two pivotally interconnected members 11 and 12 forming the mouth of the bag.

In order to retain the bag 10 in closed position as shown in Figs. 1 and 2 of the drawing, there may be provided a longitudinal channel-shaped member 14, which is adapted to fit over the top of the free edges of the separable frame to prevent separation and opening of the members 11 and 12. The channel member 14 may be suitably attached to one of the said free edges by such means as a hinge in order that it may be pivotally moved out of its closed position to a position as shown in Fig. 4, to permit opening of the bag 10. In order to retain the said channel member 14 in closed position to prevent accidental opening of the bag, I have provided a novel locking member 15 which may be suitably attached to the member 14 by such means as a pivot 16. The member 15 may comprise a short portion adapted to overlie the top of the channel member 14 and a longer portion thereof at an angle to said first portion, adapted to be disposed adjacent one side of the bag 10, when said lock 15 is in closed or operative position as shown in Figs. 1 and 2 of the drawing. To retain the member 15 in said locked position as just described I have provided a pair of catch members 17 which may be upset from the top surface of the member 14 as shown in Fig. 3, or which may be of any other suitable design, and disposed so as to resiliently engage and retain the lock 15 in position as shown in Figs. 1 and 2 of the drawing.

When it is desired to open the bag it is merely necessary to grip the lower portion of the lock 15 and exert an upward force sufficient to release the lock from the catch members 17. When the lock 15 is pivotally moved to the position as shown in Fig. 4, the channel member 14 will automatically release the free edges of the top of the bag to permit opening thereof.

By my invention I cause the above-described locking mechanism to serve as a holder for gloves, handkerchiefs and the like, arranged in such manner that it is not necessary to open or close the bag in order to operate the glove holding device.

Pivotedly mounted on the member 15 at a point such as at 20, in a pair of guides 21 is a rod member 25 having at its upper free end a ball shaped tip 26 adapted to cooperate with a pair of spaced ball shaped members 27. The said

members 27 are so designed and disposed as to function as a resilient catch for the rod 25. Thus it is seen that when it is desired to place a pair of gloves in the holder, the rod 25 is pivotally moved to the dotted line position shown in Fig. 2 of the drawing, the gloves inserted between the wall of the bag and the member 25, and the rod 25 returned to its original position between the members 27 to hold the gloves against loss. It is also apparent from the above description of the operation of my invention that the bag 10 may be opened and closed at will without the necessity of removing the gloves or disturbing the glove holding mechanism. The above feature is best illustrated in Fig. 4 of the drawing.

By my invention as disclosed in Figs. 1 to 4, it is also apparent that the glove holding device may be supported without the necessity of piercing or mutilating the material of the bag in any way.

In Figs. 5 to 8 of the drawing, there are shown modified forms of my invention.

In Fig. 5 I have illustrated a different form of locking mechanism for the bag, comprising a pair of ball tipped opposing members 30 and 31 disposed on each of the free edges of the bag and adapted to overlap each other a predetermined amount in order to act as a resilient catch to retain the bag in closed position. The rod 25' is pivotally mounted in a manner similar to that shown in Fig. 1, except that it is mounted directly on the side wall of the bag instead of to the member 15. The upper free end of the rod 25' may be curved as shown and provided with a ball 26 which is adapted to cooperate with the ball 31 to overlap the same, and act as a resilient catch therewith, similar to the arrangement of the members 30 and 31. Thus it is seen that the bag 10 may be opened or closed by manually manipulating the members 30 and 31 while the members 31 and 26 continue to remain in engaged position. Also, the members 31 and 26 may be separated without disturbing the relationship between the members 30 and 31.

In Fig. 7 I have illustrated a modified form of glove holding means used in connection with the Fig. 1 type of locking device. Instead of the rod 25 I employ an ornamental member 40 which may be pivotally secured to the lower end of the member 15 by such means as a hinge 41. The upper end of the member 40 is adapted to cooperate with a suitable catch member, such as 42. The member 40 may be held normally in closed or glove holding position as shown, by means of a spring 45, attached to the hinge 41. In Fig. 8 there is shown a glove retaining member similar to the Fig. 7 form but illustrating a different type of ornamentation, such as initials which may be removably mounted on the member 40 in any well-known manner.

In Fig. 6, I have shown my novel glove holding mechanism as applied to the envelope type of bag 50 having a locking mechanism comprising a snap fastener 51 mounted on the inner side of the overhanging flap 54 and adapted to cooperate with a catch 52 on the outer wall of the bag 50. The member 53, corresponding to the member 15 is mounted at the lower end of the flap 54 of the bag and extends downwardly as shown. The rod 25 is pivotally mounted on the member 53 in a manner similar to that shown in Fig. 1 and has at its upper free end a ball 26 adapted to cooperate with a pair of resilient catch members 27 mounted on the member 53. In this form it is also seen that the operation of the

glove holding device is independent of the opening and closing of the bag and at the same time the glove holding device is designed to serve as a convenient handle member to facilitate the opening and closing of the bag.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing, is to be interpreted as illustrative and not in a limiting sense.

Having thus described my invention, I claim as new and desire to secure by Letters Patent:

1. In combination, a bag of the character described, releasable means for retaining said bag in closed position, comprising a relatively narrow portion extending transversely along one side of the bag when in closed position, and a glove holding device mounted on said transversely extending portion, comprising an ornamented member having one end pivotally mounted on said retaining means, and means for normally urging the free end of said pivotally mounted member toward said retaining means.

2. In combination, a lady's bag of the pouch type having a frame, releasable means for retaining said bag in closed position, said releasable means comprising a relatively narrow plate extending transversely along one side of the bag when in closed position and having a portion thereof adapted to cooperate with catch means on said frame, and a glove holding device mounted on said plate comprising a rigid member having one end pivotally mounted on said retaining means and having adjacent the other end thereof a ball portion, catch means mounted on said retaining means for releasably holding the free end of said pivotally mounted member, said catch means comprising a pair of ball members adapted to frictionally receive the said rigid member between them whereby the ball portions of said rigid member and said catch members are in triangular formation, the operation of said glove holding means being independent of said bag closing device.

3. A locking device for bags of the frame or pouch type comprising a relatively narrow flat plate adapted to cooperate with catch means on said bag for releasably locking said bag, means for pivotally attaching said plate to said bag frame, a member pivotally mounted at one end thereof on said plate and catch mechanism on said plate adapted to engage the free end of said pivotally mounted member, said pivotally mounted member being movable independently of said bag locking means.

4. A locking device for ladies' bags and the like comprising a relatively narrow rigid member adapted to cooperate with catch means on said bag for releasably locking said bag and to be transversely disposed and parallel to one side of said bag when in locked position, and glove holding means mounted on said transversely disposed member, said glove holding means being operable independently of said locking means.

5. A locking device for ladies' bags and the like comprising a relatively narrow rigid member having a relatively short portion and a relatively long portion at an angle thereto, said long portion adapted to overlie a portion of one side of said

bag when in locked position, and glove holding means mounted on said rigid member, said glove holding means comprising a member pivotally mounted at one end thereof and provided with an enlarged portion adjacent the free end thereof, and a catch device cooperating with said free end, said catch device comprising a pair of spaced members having enlarged heads adapted to frictionally receive between them the free end of said pivotally mounted member, the movement of said pivotally mounted member being independent of said rigid member.

6. As an improved article of manufacture, a lady's bag of the pouch type having a frame, provided with releasable means for retaining said bag in closed position, said releasable means comprising a relatively narrow plate extending transversely along one side of the bag when in closed position and having a portion thereof adapted to cooperate with catch means on said frame, and article holding means mounted on said releasable retaining means, said holding means comprising a member having one end thereof hinged to said narrow plate and the other end thereof being adapted to cooperate with releasable catch means on said plate.

7. As an improved article of manufacture, a lady's bag of the pouch type having a frame, provided with releasable means for retaining said bag in closed position, said releasable means comprising a relatively narrow plate extending transversely along one side of the bag when in closed position and having a portion thereof adapted to cooperate with catch means on said frame, and article holding means mounted on said releasable retaining means, said holding means comprising a member having one end thereof hinged to said narrow plate and the other end thereof being adapted to cooperate with releasable catch means on said plate, said hinged member being pivotally movable independently of said means for releasably retaining the bag in closed position.

8. In combination, a bag of the character described having a frame, releasable means on said

frame for retaining said bag in closed position, said releasable means comprising a relatively narrow plate extending transversely along one side of the bag when in closed position and having a portion thereof adapted to cooperate with catch means on said frame, and a glove holding device mounted on said plate, said glove holding device comprising a member pivotally mounted on said plate, the movement of said pivotally mounted member being independent of said means for releasably retaining said bag in closed position.

9. In combination, a bag of the character described having a frame, releasable means hinged to said frame for retaining said bag in closed position, said last-named means comprising a relatively narrow plate extending transversely along one side of the bag when in closed position and having a portion thereof adapted to cooperate with catch means on said frame, and a glove holding device mounted on said plate, said glove holding device comprising a member having one end thereof pivotally mounted on said plate, and catch means on said plate whereby the free end of said pivotally mounted member is adapted to engage in said catch means, the movement of said pivotally mounted member being independent of said releasable means for retaining the bag in closed position.

10. In a bag of the character described, the combination of a frame, releasable means pivotally mounted on said frame for retaining said bag in closed position, said releasable means comprising a plate having a relatively narrow portion extending transversely along one side of the bag when in closed position, a glove holding device mounted on said transversely extending portion comprising a rod-like member having one end pivotally mounted on said retaining means, and means on said retaining means for releasably retaining the free end of said rod-like member, the pivotal movement of said rod-like member being independent of the releasable means for retaining the bag in closed position.

DAISY H. COHEN.
